UNITED STATES PATENT OFFICE.

BRUNO MILEWSKI, OF KENT, OHIO.

JOURNAL-BOX BEARING.

Application filed April 18, 1923. Serial No. 632,950.

To all whom it may concern:

Be it known that I, BRUNO MILEWSKI, a citizen of the United States of America, residing at Kent, in the county of Portage and State of Ohio, have invented certain new and useful Improvements in Journal-Box Bearings, of which the following is a specification.

This invention relates to certain new and useful improvements in journal box bearings and has particular reference to the lubrication of the end of a shaft extending into and journaled in the box with means associated with the end of the spindle or shaft to prevent the lubricant saturated fiber or packing material from being moved into contact with the upper bearing surfaces for the shaft or spindle.

With the above and other objects in view as the nature of the invention is better understood, the same consists of the novel form, combination and arrangement of parts hereinafter more fully described, shown in the accompanying drawing and claimed.

In the drawing wherein like reference characters designate like parts throughout the several views,

Figure 1 is a vertical longitudinal sectional view of a journal box bearing showing the fibre holding device associated with the end of the spindle or shaft within the journal box to prevent the lubricated fiber or like material from being conveyed upwardly to the bearing surfaces for the shaft,

Figure 2 is a top plan view of the journaled end of the shaft with the fibre holding device in its operative position,

Figure 3 is an end elevational view of the shaft shown in Fig. 2,

Figure 4 is a fragmentary end elevational view showing an arm of the holding member inclosing the inner end of the shaft,

Figure 5 is a perspective view of the fibre holding member showing the bent wire formation thereof,

Figure 6 is a fragmentary end elevational view, similar to Fig. 5 showing a modified form of frame, and

Figure 7 is a fragmentary perspective view of the frame shown in Fig. 6.

Referring more in detail to the accompanying drawing, there is illustrated a box 1 supported by the bracket 2 and having an outer end opening door 3 permitting access to the interior of the box as illustrated in Fig. 1 for the placing of fiber, waste or simi-

lar material 4 to be saturated with the desired lubricant. The inner wall 5 has an opening through which the shaft 6 rotatably extends with the end 7 thereof disposed within the box and having a terminal annular flange 8 of the usual form.

An arcuate bearing plate 9 is positioned above the end 7 of the shaft and is maintained in engagement therewith by the block 10 as shown in Fig. 1, flat contacting faces being provided between the bearing 9 and block 10 while the latter is interlocked with the box 1.

The fibre holding member is associated with the end 7 of the shaft to prevent the lubricant saturated material 4 from passing upwardly to the bearing member 9, the member being preferably formed of wire as shown in Figs. 1 and 5 and bent from a single piece to provide an intermediate cross bar 11 having right angularly bent ends 12 that are further bent as at 13, the cross portion 11 traversing the outer face of the flanged head of the shaft end while the bent end portions 12 and 13 enclose the end flange 8 and are spaced therefrom, as illustrated. The wire section is continued to provide side arms 14 and have the ends thereof reversely bent as at 15 with the terminal ends of the portions 15 bent to provide clamping socket portions 16 that resiliently engage outwardly directed lugs 17 formed on the lower edges of the arcuate bearing 9 as shown more clearly in Figs. 1 to 3. With the fibre positioning device so formed, the clamping ends 16 thereof resiliently engage the laterally positioned lugs 17 upon the bearing 9 while the bent ends 12 and 13 of the cross portion 11 are spaced from the flanged head 8 of the bearing ends 7, the side portions 14 being spaced from the opposite sides of the shaft end 7 for the purpose of holding down the lubricant saturated material 4 and preventing the same from being carried upwardly between the shaft end 7 and the bearing 9.

In the form of the invention shown in Figs. 6 and 7, the bent ends 12 of the form as illustrated in Fig. 4 are flattened as at 12^a to provide relatively wide blades that positively hold the lubricant saturated material properly positioned in the box against the peripheral edge of the shaft flange 8.

While there are herein shown and described the preferred embodiments of the present invention, it is nevertheless to be

understood that minor changes may be made therein without departing from the spirit and scope of the invention as claimed.

What is claimed as new is:—

1. In a journal box bearing and lubricator, a bearing box containing lubricant saturated material, a shaft end extending into the box and dipping into the material, a bearing interposed between the upper side of the box and shaft end, a lug projecting from each side of the bearing, and a wire hold-down for the saturated material having side portions positioned in spaced relation to the shaft end and arms extending having clamp ends engaging the bearing lugs to prevent conveying of the material upon rotation of the shaft end.
- 10 2. In a journal box bearing and lubricator, a bearing box containing lubricant

saturated material, a shaft end extending 20 into the box and dipping into the material, a bearing interposed between the upper side of the box and shaft end, a lug projecting from each side of the bearing, and a wire 25 hold-down for the saturated material, said hold-down comprising an intermediate cross bar traversing the shaft end, angularly bent end portions carried by said cross bar spaced from the shaft end, side arms formed with 30 said end portions extending longitudinally of the shaft, and reversely bent end portions carried by the side arms having clamping socket portions resiliently engaging the lugs carried by the bearing member.

In testimony whereof I affix my signature.

BRUNO MILEWSKI.
